UNITED STATES PATENT OFFICE.

JOHN H. GLATT, OF ROCHESTER, NEW YORK.

CIGAR-MOISTENER.

No. 911,392.

Specification of Letters Patent.

Patented Feb. 2, 1909.

Application filed November 4, 1908. Serial No. 461,036.

To all whom it may concern:

Be it known that I, JOHN H. GLATT, a citizen of the United States, residing at Rochester, in the county of Monroe and State of New York, have invented certain new and useful Improvements in Cigar-Moisteners; and I do hereby declare the following to be a full, clear, and exact description of the invention, such as will enable others skilled in the art to which it appertains to make and use the same.

This invention relates to improvements in moisteners for cigar boxes, and has for an object the provision of means that may be readily inserted or removed from a cigar box, and one that will effectually keep in a properly moistened condition the cigars in the box to which the same is secured.

Another object of the invention is the provision of a moistener arranged with a receptacle for receiving an absorbent material, the receptacle being so arranged as to permit the ready evaporation of moisture from the absorbent material but will not permit any contact with the absorbent material.

A still further object of the invention is the provision of a moistener that may be secured to the lid of a cigar box by having a clamping member passing over the edge of the lid.

Another object of the invention is the construction of a moistener simple in design yet thoroughly accomplishing the purposes for which it is constructed by the provision of means for sustaining liquid in suspension and clamping the edge of the lid of the box to which it is applied.

Another object of the invention is the construction of a hook shaped clamping spring that may extend for only a short distance over the lid of the box to which the moistener is secured, or the full width of the box, the spring accomplishing a double purpose; namely, the clamping of the receptacle for holding the moisture in position, and the presenting of a surface upon which advertising matter may be readily applied.

With these and other objects in view the invention comprises certain novel constructions, combinations and arrangement of parts as will be hereinafter more fully described and claimed.

In the accompanying drawings: Figure 1 is a perspective view of a cigar box with an improved moistener secured thereto. Fig. 2 is a section through Fig. 1 approximately on

line 2—2. Fig. 3 is a perspective view of a spring used in securing the moistener in place. Fig. 4 is a plan view of the moistener with the receptacle for containing the absorbent material partially removed from its support. Fig. 5 is a section through Fig. 4 approximately on line 5—5. Fig. 6 is a section through Fig. 4 approximately on line 6—6. Fig. 7 is an enlarged fragmentary view approximately on line 7—7 of Fig. 4, showing the receptacle for holding the absorbent material closed upon its support.

In the construction of my improved cigar moistener the same has been so formed as to be readily applied or detached from the lid of a cigar box, and when applied not to injure the cigars contained in the box. In forming the moistener a piece of some light sheet metal is taken and formed into a comparatively flat receptacle into which an absorbent material, as for instance, blotting paper, cork, sponge, or the like is placed. The receptacle is formed with edges that are bent over that act as ways into which a back or support is slidingly fitted. The receptacle opposite the back that is slid into place is formed with a plurality of apertures or with a foraminous surface in order to permit the moisture contained by the absorbent material to keep the cigars in proper condition. The sliding back is formed with a hook shaped portion and is adapted to hook over the edge of the lid of the cigar box and in order to properly hold the same in place a spring is fitted over the hook shaped part in the back which positively causes the same to grip the lid of the cigar box. By this construction and arrangement all that is necessary to properly apply the moistener to a cigar box is to first submerge the moistener so that the absorbent material carried thereby may be saturated and then apply the hook shaped portion over the edge of the lid, the moistener previous to its application being wiped off so as to be free from any liquid not held by the absorbent material.

In order to more clearly disclose the invention I have shown one embodiment in the accompanying drawings in which—

1 indicates a cigar box of any desired kind, and 2 the lid to which is attached the moistener. Preferably in constructing a moistener the same is adapted to occupy a considerable portion of the lid in order to

properly distribute moisture to the cigars in the box. The moistener is formed with a receptacle 3 that has provided in its face a plurality of apertures 4 that form in reality a foraminous face through which the moisture in the absorbent material 5 may pass into the box for maintaining the cigars in proper condition when the lid is closed. The receptacle 3 is formed with bent over 10 sides 6—6 into which is slid a supporting back 7 that covers the entire back of the receptacle 3 and extends over the edge of the lid 2 when in use. The part that extends over the edge of the lid 2 is formed into a hook 8, the hook 8 being of the same width as the main body part of the back that is slid into members 6—6. A spring clip 9 is forced over the hook shaped member 8 and normally holds the same against lid 2 20 when the moistener is in operation. Any desired kind of advertising matter may be placed at point 10 on hook 8 and clip 9 which is exposed to view when the lid 2 is closed.

25 Formed in back 7 near the upper end thereof are a plurality of projections 11 and a plurality of projections 12. The projections 11 are adapted to have the upper end 13 of receptacle 3 moved upon the same, and 30 by such movement is wedged against accidental movement. The projections 12 are adapted to limit the downward movement of the moistener when applying the same to the lid of a cigar box for properly positioning the face of the receptacle 3. The hook shaped member 8 is formed with a flared end 14 preferably in order to permit an easy application of the moistener to the box.

When it is desired to apply a moistener to 40 a box of cigars the absorbent material 5, which may be blotting paper, sponge, cork or the like, is taken and submerged in water or is first placed in the receptacle and then submerged until saturated, after which the 45 back 7 is placed in position and the hook 8 is forced over the upper edge of the lid 2. This will cause the receptacle 3 to be mounted upon the lid 2 with its foraminous face downward when the lid is closed in immediate proximity to the cigars in the box. When the lid is closed the receptacle 3 can 50 not be pressed very hard against the cigars because of the resistance of the spring 9 and back 7 which are in engagement with the

edge of the box, and hold the lid slightly 55 raised. Whenever the moisture in the absorbent material 5 is desired to be renewed all that will be necessary is to pull against the hook shaped member 8 and the same may be easily slipped off the lid of the box, together with the remaining part of the moistener. The absorbent material 5 may then be supplied with moisture and the moistener again placed in position. From this it will be observed that the moistener may be applied and removed whenever desired either to the same box or on a new box without marring the box and without injuring the moistener.

The moistener has been described more 70 particularly in relation to a cigar box, but it will be evident that the same may be used in connection with other boxes or in other places whenever desired without departing from the spirit of the invention. The construction and arrangement of means for holding moisture and means for clamping the device in position permit the application and removal of the moistener as often as 75 desired.

80 What I claim is:

1. In a device of the character described, a receptacle, means for carrying moisture mounted in said receptacle, a back for said receptacle formed with a pressed out portion over which parts of said receptacle are adapted to be forced for clamping the receptacle to said back, a curved extension projecting from said back for holding the back and receptacle in position, and clamping means substantially inclosing said extension for clamping the extension in position.

2. In a device of the character described, a receptacle, a liquid carrying material positioned in said receptacle, a sliding back for 95 said receptacle formed with pressed out portions over which parts of said receptacle are adapted to be forced for clamping the receptacle to said back, a hook shaped member projecting from said back, and spring means 100 for clamping said hook shaped member in position.

In testimony whereof I affix my signature in presence of two witnesses.

JOHN H. GLATT.
